(57) **CLAIM**

The ornamental design for a micro-column gel card, as shown and described.

DESCRIPTION

FIG. 1 is a front view of a micro-column gel card showing our new design;

FIG. 2 is a rear view of the micro-column gel card of FIG. 1;

FIG. 3 is a left side view of the micro-column gel card of FIG. 1;

FIG. 4 is a right side view of the micro-column gel card of FIG. 1;

FIG. 5 is a top view of the micro-column gel card of FIG. 1;

FIG. 6 is a bottom view of the micro-column gel card of FIG. 1; and,

FIG. 7 is a perspective view of the micro-column gel card of FIG. 1.

The present product is used as a gel pouring container of a micro-column gel diagnostic reagent product.

The broken lines in the drawings depict portions of the micro-column gel card that form no part of the claimed design.
